UNITED STATES PATENT OFFICE

2,418,213

SLAB MARKING DEVICE

Frederick Winterkamp, Youngstown, Ohio, assignor to Carnegie-Illinois Steel Corporation, a corporation of New Jersey

Application June 20, 1944, Serial No. 541,241

3 Claims. (Cl. 101—4)

1

The present invention relates to improved means to facilitate the marking of either the end or side edges of slabs, billets, or similar work-pieces.

One object of the invention is to provide simple yet effective means to facilitate the stamping of identifying marks on the ends as well as the sides of slabs, billets, or the like, in such manner that the marking is always visible when such work-pieces are stacked in storage.

A further object is to provide means for supporting fluid-operated marking devices on an arm swingable to a predetermined position for engagement with either the end or side edge of the slab or like workpiece, in such a way that the marking devices have a swivel connection with the arm so that the latter need not necessarily be accurately aligned with the end or side edges of the workpiece.

The above and further objects of the invention will be fully apparent from the following detailed disclosure when read in connection with the accompanying drawings and the appended claims.

In the drawings:

Figure 1 is a plan view of a slab or billet run-out conveyor table having juxtaposed thereto a marking device incorporating the herein claimed invention.

Figure 2 is a side elevation of the apparatus of Figure 1.

Figure 3 is a section on line III—III of Figure 2.

Figure 4 is a fragmentary plan of Figure 3.

Figure 5 is a horizontal section on line V—V of Figure 3.

Figure 6 is a detail section on line VI—VI of Figure 1.

Referring in detail to the drawings, 10 represents one side frame of a conventional form of slab or billet run-out table, usually equipped with a multiplicity of power-driven conveyor rolls 12. Mounted in juxtaposition to the run-out table is a bracket or frame member 14 rotatably supporting a pedestal 16 in aligned bearing portions 18. At its upper end the pedestal carries a stub shaft 20 serving as a fulcrum support for an arm 22, which is apertured at 24 to provide clearance with respect to the upper end of the pedestal. An adjusting screw 26 is threaded through the hub 28 of the arm, and provides means for adjusting or leveling the arm so that identifying marks or indicia can be located or spotted with precision on either the end edge e or the side edge s of the slab or billet B supported on the table.

2

A holder 30 is swiveled on a vertical bolt 32 which is adapted to be adjusted at a desired radial distance from the axis of rotation of the pedestal 16. An angle 34 is secured by a bolt 36 in one of several holes 38 located at radial distances to suit the particular work to be marked. The angle 34 acts as a stop to limit the extent of swiveling motion of the holder about the axis of the bolt 32. The holder carries one or more U-shaped straps 40 each of which is adapted to support a pneumatic hammer 42 having a head 44 carrying suitable type-like marking tools 46. A control stand 48 is mounted adjacent the marking device, and has individual control valves 50 for each of the marking devices 46, there being a supply pipe 52 connected with a suitable source of fluid pressure, each valve 50 controlling the passage of motive fluid to a flexible tube 54 leading to the pneumatic tool 42.

For swinging the arm 22 about the vertical axis of the pedestal 16, I provide a fluid-actuating cylinder 56 having a suitable piston therein for reciprocating a piston rod 58 carrying a rack 60 meshing with a pinion 62 secured to the lower portion of the pedestal 16. A valve 64 controls the supply of motive fluid fed from pipe 66 to the cylinder 56 by way of a pipe 68. A plunger 70 reacting against a spring 72 carried in a cylinder 74 suitably mounted in a bracket 76 serves to cushion the swinging action of the parts.

In normal operation, for marking identifying numbers or letters on the end face e of the slab or billet, the arm 22 will occupy the full-line position shown in Figure 1. With the parts in this position, it is merely necessary for the operator to admit compressed air by a manipulation of the valve 50, whereupon the pneumatic hammer 42 will cause the tools 46 to indent suitable marks on the end edge e of the slab or billet. By manipulating the valve 64, compressed air is admitted to one end of the cylinder, thus swinging the arm 22 to the dotted-line position indicated at 22^a. This will move the marking devices 46 to the position shown in dotted lines, so as to facilitate applying identifying marks to the side edge s of the billet. When in this position it will be apparent that the swivel connection 32 provides an arrangement whereby the holder can be properly brought into substantial parallelism with the side edge S of the billet while the arm 22 makes an acute angle therewith, as indicated by the dotted showing 22^b. As shown in the dotted position 22^b, the arm is adapted to be withdrawn to a position so as to bring the marking devices 55 to a location immediately adjacent the control

bracket 48 and thus to a point convenient to the operator for making the desired changes in the marking tools 46, to suit identification requirements.

While I have described quite precisely a preferred construction of the embodiment of the invention illustrated, it is to be understood that the drawings and description are to be interpreted in an illustrative rather than a limiting sense.

I claim:

1. An apparatus of the character described, comprising a support for a rectangular workpiece to be marked, an arm swingably mounted in juxtaposition to said support, a marking device carried by a holder swiveled on the arm, means on said arm limiting the swiveling motion of said holder, and means for swinging the arm to a plurality of positions with respect to said support so as to selectively position the marking device for coaction with either the end or side upright edges of the workpiece on said support.

2. An apparatus of the character described, comprising a conveyor adapted to support rectangular slabs or billets, a marking station comprising a pedestal located in juxtaposition to the conveyor, an arm rotatably supported by the pedestal and adapted to be swung over a portion of said conveyor, a holder swiveled on said arm adjacent the free end thereof, means on said arm limiting the swiveling motion of said holder, a marking device supported in the holder and adapted to make impressions on either an end or side upright edge of said slabs or billets, and power means for swinging said arm to predetermined positions.

3. An apparatus of the character described, comprising a support for a rectangular slab to

be marked, a swingable arm mounted in juxtaposition to the support, a holder having a swivel connection with said arm, a stop limiting the movement of said holder about said swivel connection, a fluid-operated marking device supported by said holder, fluid-operated means for swinging said arm to predetermined positions to facilitate the making of impressions by said marking device on either the end or side up-

right edges of the slab, a control station including one valve having a flexible connection with the fluid-operated marking device and controlling the actuation thereof, and another valve controlling the supply of fluid to said arm-operating means.

FREDERICK WINTERKAMP.
